UNITED STATES PATENT OFFICE

2,065,979

MANUFACTURE OF HOSIERY

Paul Lieberknecht, Einsiedel, near Chemnitz,
GermanyApplication December 21, 1934, Serial No. 758,578
In Germany March 13, 1934

2 Claims. (Cl. 66—187)

This invention relates to a method of producing stockings, socks and the like having French heels on flat, full-fashioned hosiery machines, according to which the leg and foot are made with the same continuous thread or threads in one operation and the heel is worked subsequently. The present invention is an improvement over the disclosure in applicant's prior Patent No. 2,027,781 of January 14, 1936.

10 It has been proposed to effect the transition from the leg to the foot partly with and without the aid of separately made auxiliary portions, the latter being intended to facilitate the transferring of the initial courses of the side portions 15 of the foot on the linking machine. When no auxiliary pieces are employed, the first part of the foot cannot be made wider than the stocking at the end of the leg, as otherwise there would be no structure for holding the goods during the transfer to the linking machine.

20 It is the object of the invention to produce a stocking of the kind mentioned above without separately worked auxiliary portions, that is, a stocking in which the beginning of the foot may be any number of needles wider than the end of the leg to attain any desired fit of the hose structure at the ankle-joint relative to the heel.

According to the invention, prior to the working on of the separating courses when passing from the leg to the foot, the width of which towards the inside is smaller than that of the heels, and during the working of the last courses of the leg, an auxiliary part is worked beside them and to the left and right of the leg on the same needle bar at the point, provided for widening the foot, whereupon, after the finishing of the separating courses, the foot is started as much wider as the auxiliary portions indicate and, after the finishing of the foot part and subsequent transferring of the heel portions to the heel machine for the attachment of the heel parts, the entire structure of the side and middle portions of the foot positioned above the heel needles, together with the separating courses, is brought over and beyond the needle points to the backs of the needles, either before or after the formation of the first heel course; finally, after the heel has been worked on, one of the first courses of the middle portion of the foot is transferred to the needles of the linking machine and the separating courses are destroyed, whereupon the inner edge of the heel is united on the needles of the linking machine with the respective course of the side portion of the foot and the auxiliary parts are removed.

By way of example, the invention is illustrated in the accompanying drawing, in which Figure 1 shows the middle portion of a stocking produced according to the invention, a special thread guide having been used for producing each auxiliary portion; and Fig. 2 shows a similar middle portion, in which the auxiliary portions have been produced by the same yarn guide that has worked also the high heel.

Referring to the drawing, while approximately 10 the last fifty courses of the leg *a* are worked, the auxiliary portions *d*, *d'*, corresponding about to the widenings *f*, *f'* of the first part *b* of the foot, are simultaneously produced on the same needle bar. Before the foot part is made, the separating 15 courses *e*, *e'* are worked from both edges *u*', *u''* of the leg within the heel width shown, which are somewhat shorter towards the middle of the structure than the heel portions themselves are wide, while the working of the middle portion *b'* 20 of the stocking is continued.

The separating courses *e*, *e'* in the middle portion of the stocking shown extend also across the auxiliary portions *d*, *d'*, though it is possible to have them terminate in front of them. Then 25 the foot part is started and completed, after which step the joined leg and foot are taken off from the machine and directly or indirectly transferred to the heel machine, whereupon the heels are worked on in the usual way. After completion of the heels one of the first courses of each middle foot portion is transferred to the linking machine. The separating courses are then destroyed and the inner edges of the heels united 30 on the linking machine with the side portions of the foot and, simultaneously, both auxiliary portions 35 removed.

In the structure shown in Fig. 1 the auxiliary portions *d*, *d'* are worked by separate yarn guides. As Fig. 2 indicates, the auxiliary portions can be 40 worked also without the help of separate yarn guides by causing the guides or carriers of the high heel thread or ground thread or both guides to continue working for the requisite distance beyond the left and right-hand edge of the leg 45 and thus form the auxiliary portions.

By separating courses is understood mesh courses or parts of such similarity as produced in the other mesh courses. They differentiate from them, however, by the length of the mesh course and by the color or thereby that the separating course consists merely of one thread while the meshes of the high heel with those of the sole parts consist of two threads. The name separating courses means that the mesh course is for 50 55

the purpose of subsequently being ripped open or cut open and for this purpose it must be easily recognizable. Separating courses may be made in accordance with U. S. Patent No. 1,665,972 in which on page 2, line 70 thereof reference is made to the guide line courses θ . In accordance with the present invention, the separating course sections are of lesser length than the width of the heel sections which are indicated on the accompanying sketch by the reference characters g and g' . The separating course e extends thus from the point h to the point i while the heel part g extends from the point h to the point k and is securely connected with the leg and foot. A clearer explanation will be submitted in the following:

First the leg a is produced. During the fabrication of the last mesh course of the leg a the particular auxiliary portions d and d' are simultaneously knitted adjacent thereto, which are however not heel parts, but are later removed from the hose. These auxiliary portions serve the purpose of maintaining the meshes which are on the needles adjacent those which produce the leg a .

If one begins the knitting of an auxiliary portion then the meshes will not be uniformly formed at the beginning on all of the needles but merely sporadically, and one must knit a plurality of mesh courses, at times twenty to fifty courses, before the thread will be taken up by all the needles. Such auxiliary portions are called preliminary courses. The parts d and d' are therefore nothing more than starting courses.

When the legs are produced the short separating courses are provided on both of its sides. Thereafter the foot part b' is knitted in its required width. It is wider than the end of the leg a and it not only projects over the width of the leg a but extends out to the auxiliary portions d and d' . The middle portion b' consists of the middle foot part and of two sole parts.

When the foot part b is finished the hose is removed from the particular knitting machine and, by means of the separating courses e and e' to which the heel portions g and g' are to be added, impaled on the needles of another knitting machine. In order that one can knit the heel portions without any difficulties, the leg a as well as the foot parts b' , b are brought to the underside of the knitting needles, as clearly described in applicant's Patent No. 2,027,781. Now the heel parts g and g' are knitted to the hose in which the operation is carried out in a manner similar to the operation in knitting the leg a and the portions b' , b . The machine for making the heels is a similar flat knitting machine as the machine for knitting the legs. It is, however, so set that the thread guide only passes over short mesh course pieces, since each of the two heel parts g and g' are considerably smaller than the legs a . The mesh courses of the heel parts g and g' will therefore be knitted quicker than the leg parts. Thus the heel machine can operate appreciably quicker than the leg machine.

When the heel portions g and g' are completed its edges l and l' must be connected with the beginning of the sole parts c and c' longitudinally of the separating courses e and e' . This is carried out in known manner by means of a so-called Kettel machine. On the needles of the latter the first mesh course of the sole parts c and c' are impaled thereon. Then the separating courses e and e' are ripped or cut open whereby the auxiliary portions d and d' are

separated therefrom and a slit will be formed between the foot parts c and c' and the leg a which will have such a separation depending upon the length of the separating courses e and e' . Then the edges l and l' of the heel portions g and g' are impaled on the needles of the Kettel machine and are connected with the beginning of the foot parts c and c' in known manner.

The aforementioned method which constitutes the subject matter of the present application differentiates from the method disclosed in applicant's German Patent No. 591,694 thereby that the beginning of the foot parts b' , c and c' are wider than the end of the leg part without it being necessary for this purpose to utilize specific auxiliary portions which would have to be produced in a special way and would take considerable time to impale them on the needles of the knitting machine. The new method in accordance with the present application permits a hose to be fabricated in much quicker time. The auxiliary portions are not impaled on the specific needles which fabricate the separating courses e and e' but they are knitted while the last mesh course of the leg part is fabricated and by a specific thread guide without it being necessary to utilize any further time in the manufacture of the hose. They are narrower than the auxiliary portions which according to the German patent, referred to, are to be utilized in the manner set forth.

The auxiliary portions d and d' which according to the present invention are knitted adjacent the middle mesh course of the leg part are of entirely different nature than the portions u and u' which are disclosed in the Hilscher patent adjacent the foot part. The parts u and u' in accordance with Hilscher are heel portions. They correspond to the parts g and g' of applicant's invention and as a matter of fact Hilscher admits that the heel parts u and u' have a continuation of the main portion of the hose whereas according to the present invention the auxiliary portions d and d' begin their fabrication without the necessity of knitting another portion on the particular needles on which they are produced and to which the parts d and d' could be connected. The auxiliary portions d and d' have, as a matter of fact, a purpose to permit the courses to be maintained on the needles of each section of the knitting machine which will then permit the formation of the sole parts c and c' also on these needles but upon the ends of which part a is not knitted. There are, therefore, many differences between the needle parts u and u' of Hilscher which are adjacent the foot portion, and the auxiliary portions d and d' which the applicant provides adjacent the part a . Apart from this it is to be noted that the knitting of the auxiliary portions d and d' according to the present invention is to be considered only in the specific construction of a hose but not as a method in constructing the auxiliary portions themselves.

I claim:

1. A method of producing a stocking on a flat full-fashioned hosiery machine while working the foot directly onto the leg without transferring, which comprises in producing, prior to the working of the separating courses when passing from the leg to the foot, whose width towards the inside is smaller than that of the heels, and during the working of the last courses of the leg, an auxiliary portion adjacent thereto and to the right and left of the leg on the same needle bar at the point provided for widening the foot portion,

starting the foot after the finishing of the separating courses as much wider as the auxiliary portions indicate, transferring, after the finishing of the foot part and the subsequent transferring of the heel portions to the heel machine for attaching the heel portions, the entire structure of the side and middle portions of the foot located above the heel needles, together with the separating courses, over and beyond the needle points to the backs of the needles before the formation of the first heel course, transferring after working on the heel one of the first courses of the middle portion of the foot to the needles of

a linking machine, removing the separating courses, uniting the inner edge of the heel on the needles of the linking machine with the respective course of the side part of the foot, and removing the auxiliary parts.

2. A method according to claim 1, in which the moving of the entire structure of the side and middle portions of the foot located above the heel needles, together with the separating courses, over and beyond the needle points to the backs of the needles is carried out after the formation of the first heel course.

PAUL LIEBERKNECHT.
